(57) **CLAIM**

The ornamental design for an architectural fixture, as shown and described.

DESCRIPTION

FIG. 1 is a top, front, left perspective view of an architectural fixture showing our new design;

FIG. 2 is a front elevation view of the architectural fixture of FIG. 1;

FIG. 3 is a rear elevation view of the architectural fixture of FIG. 1;

FIG. 4 is a left side elevation view of the architectural fixture of FIG. 1;

FIG. 5 is a right side elevation view of the architectural fixture of FIG. 1;

FIG. 6 is a top plan view of the architectural fixture of FIG. 1;

FIG. 7 is a bottom plan view of the architectural fixture of FIG. 1;

FIG. 8 is a top, front, left perspective view of a second embodiment of an architectural fixture, showing our new design;

FIG. 9 is a front elevation view of the architectural fixture of FIG. 8;

FIG. 10 is a rear elevation view of the architectural fixture of FIG. 8;

FIG. 11 is a left side elevation view of the architectural fixture of FIG. 8;

FIG. 12 is a right side elevation view of the architectural fixture of FIG. 8;

FIG. 13 is a top plan view of the architectural fixture of FIG. 8; and,

FIG. 14 is a bottom plan view of the architectural fixture of FIG. 8.

The claimed architectural fixture is used for architectural systems, acoustical systems, ceiling panels, walls panels, and other exterior and/or interior panel systems.

1 Claim, 10 Drawing Sheets
